UNITED STATES PATENT OFFICE.

HARRY C. GAMMETER, OF CLEVELAND, OHIO, ASSIGNOR TO THE AMERICAN MULTIGRAPH COMPANY, OF CLEVELAND, OHIO, A CORPORATION OF OHIO.

DEVICE FOR TREATING LINOTYPE-SLUGS.

1,122,729.

Specification of Letters Patent. Patented Dec. 29, 1914.

Application filed April 30, 1914. Serial No. 835,478.

To all whom it may concern:

Be it known that I, HARRY C. GAMMETER, a citizen of the United States, residing at Cleveland, in the county of Cuyahoga and State of Ohio, have invented a certain new and useful Improvement in Devices for Treating Linotype-Slugs, of which the following is a full, clear, and exact description, reference being had to the accompanying drawings.

My prior application No. 783,722, filed August 8th, 1913, describes and claims a process of making printing line slugs having lugs on their opposite sides and standing a short height-to-paper, the object being to provide slugs suitable for use in a slotted or railed form holder like the multigraph drum, flexotype blanket, an address plate, etc. Briefly, such process includes the casting of a T-shaped slug with up and down ribs on its opposite sides leading to the shoulder provided by the overhanging head of the slug; then treating this slug to remove the portion of the ribs immediately adjacent to the head and remove the lower portion of the slug, producing the desired short-height slug with side lugs.

The object of the present invention is to provide an efficient machine for so treating the originally cast slugs.

The machine is hereinafter more fully described and its essential characteristics set out in the claims.

In the drawings, Figure 1 is a plan of my machine partly broken away; Fig. 2 is a vertical section on the line 2-2 of Fig. 1; Fig. 3 is a vertical section on an enlarged scale substantially on the offset line 3-3 of Fig. 1; Fig. 4 is an end view of the machine on the same scale as Figs. 1 and 2; Fig. 5 is a perspective view of a portion of the originally cast slug to be treated by this machine; Fig. 6 is a perspective view of the same after treatment, and Fig. 7 is an exaggerated detail of portions of the slug-treating dies.

The present machine is a combined pressing and cutting-off device which operates on the slug A shown in Fig. 5 to mash the upper portion of the ribs a immediately below the head a¹ of the slug, and at the same time to cut off the lower portion of the ribs and the lower portion of the slug body to provide the slug shown in Fig. 6. In the

latter figure, A¹ represents the remaining portion of the body and a² the remaining portion of the ribs, the upper portion of the ribs being flattened so that they were almost flush with the sides of the body, as shown at a³.

The frame of the machine consists of a bed 10 of suitable form which is shown as provided with ears 11 and 12 by which it may be secured to a table or other support. Rigidly clamped on this frame is a stationary die 15, and slidably mounted on the frame is a cooperating movable die 16 which is adapted to be moved toward and from the stationary die. These two dies are provided with knives 17 and 18 which coact to slice off the lower portion of the slug which is placed between them. They are also provided with blades 19 and 20 which operate, as hereinafter described, to mash the upper portion a² of the ribs of the slug. The line slug is properly centered for the action of the blades and knives by the engagement of the dies 15 and 16 with the opposite sides of the T-head of the slug. The slug ready for treatment is shown at A in Fig. 1, the finished slug is shown at A¹, and a cut-off portion at A² in Figs. 2 and 3, such cut-off portion dropping through the opening 13 in the bed.

The stationary knife 17 is adjusted accurately by set screws 25 screwing through the frame and bearing against the edge of the die, and the adjusted die is clamped by screws 26 passing through slightly elongated or enlarged holes in the die, as will be well understood. The movable die 16 is adjusted by set screws 29 in the upper portion of the block, which screws are locked by clamping screws 30. The die is clamped to the block in adjusted position by the screws 31. The block 28 is guided on the bed plate by having inclined end ribs 33 and 34 which slide along the guideways provided by the bed plate and overhanging inclined bars 35 and 36 held to the bed by screws 37 and 38. The rear edge of the block 28 is inclined and coacts with a wedge 40 which is longitudinally movable and is slidably held to the block 28 by means of an upwardly projecting rib 41 occupying a groove in the under face of the block near its rear. The result is that, if the wedge is shoved longitudinally, the block 28 is moved

forward or backward carrying the movable die toward or from the stationary die.

To conveniently slide the wedge 40 it is provided on its rear face with a rack 42 which meshes with the teeth on a segment 43. The segment is pivoted on a screw pin 46 and beyond the pivot is bent or formed into a lever 47. The movement of the lever shifts the wedge 40 and this operates the movable die. The rack is shown as fitting snugly in a recess in the wedge, and holes 43 are provided to enable it to be driven out for repair. The wedge is provided with a guiding rib 49 extending into a groove in the bed plate parallel with the face of the die, and the movement of the wedge is limited by set screws 50 and 51 mounted in bracket arms 52 and 53 of the frame.

As heretofore stated, the stationary and movable dies carry blades 19 and 20 respectively. These blades seat in kerfs in the dies which are of such depth that, in operation, the bottom or inner face of the kerf contacts with the edge of the blade and the die and blade operate as a unit. The blades are rabbeted at their forward edges, as shown at 60 in Fig. 4, so that they are adapted to engage and mash the upper portion of the ribs without contacting with the lower portion. To enable the blades, however, to support the inserted slug when the dies are open, the blades are made slightly movable toward each other by means of springs 61, which are mounted in the respective dies and bear against the outer edges of the blades. The movement of the blades toward each other is limited by pins 62 engaging slots in the blades.

By reason of the spring pressed blades described, when the dies are separated there is provided a space between them sufficient for the convenient insertion of the body portion of the slug. The blades, however, are always close enough together to extend beneath the head α^1 of the slug and support it. Accordingly, when the blades are separated, the slug may be put in place, and then a movement of the lever 47 forces the movable die toward the stationary die, which causes the blades to travel relatively backwardly in their respective dies until seating firmly within the dies, so that, as the knife edges 17 and 18 come practically together to shear off the lower portion of the ribs and body, the blade edges above the rabbets have engaged and mashed the upper portion α^3 of the slug ribs. Then, on the reverse movement of the lever 47, the lower cut-off portion A^2 of the slug is released and drops through the opening 13 in the bed and the upper portion A^1 is finished and ready to be removed.

To insure the slug to be treated being firmly seated in the dies so that the ribs will be mashed down immediately adjacent to

the head of the slug (so that the printing pressure of the finished slug will be taken by the original cast under surface of the head), I provide a pressing device consisting of a roller 70 on the shaft 71 mounted in rock arms 72 pinned to a rock shaft 73. Rigid on this rock shaft is a hand lever 74. When the lever 74 is swung over, the roller is pressed down on the face of the slug, which presses the head down firmly on the blades 19 and 20. The upper faces of the blades are slightly inclined downwardly, as shown in exaggerated form at 65 in Fig. 7, so that sharp edges are provided onto which the head α^1 is forced by the roller 70. This line-engagement enables an ordinary hand pressure on the lever 74 to hold the head firmly on the dies so that they act on the ribs immediately adjacent to the head.

To prevent the roller 70 injuring the characters cast on the face of the slug I make it slightly yielding. For example, it may conveniently be made of hard rubber. The movable die turns the roller slightly with each impression, so that a fresh face is continually presented and an even wear is insured. A suitable set screw 76 mounted in an ear 77 projecting from the lever 74 is adapted to abut the die 15 and form a stop for the downward movement of the roller.

In operating my machine, the slug A, as shown in Fig. 5, is inserted between the dies by hand or any suitable mechanism. It may be conveniently shoved in endwise between the dies and dropped. With the slug in this position the operator, with one hand, swings over the lever 74, holding the slug down on the blades 19 and 20 and, with the other hand, operates the lever 47, thus cutting off the lower portion of the slug and mashing the ribs as described. Then, when the two levers are returned to normal position, the bottom portion of the slug drops through the opening 13, as illustrated in Fig. 3. When the next slug is inserted from the end of the space between the dies, it shoves out the finished slug from the opposite end of the machine.

It will be seen that, where only a hand operation is desired, it is convenient for the operator to stand facing the edge of the machine shown at the bottom of Fig. 1; then to insert the fresh slug with the right hand from a convenient supply and receive the shoved out finished slug with the left hand and place it in a suitable receptacle; then to shove over the lever 74 with the right hand and pull on the lever 47 with the left hand, completing the treatment of the new slug. It is to be understood that, if desired, mechanism may be provided for performing these hand operations; that is, mechanism which feeds in the fresh slug and removes the finished slug and operates the levers 74 and 47.

Having thus described my invention, what I claim is:

1. The combination, with means for holding a slug having a T-head and up-and-down side ribs, of means for mashing a portion of such ribs immediately beneath the head while leaving a portion farther from the head.
2. The combination, with means for holding a slug having a T-head and up-and-down side ribs, of means for mashing a portion of such ribs immediately beneath the head while leaving a portion farther from the head, and means for cutting off the slug body some distance below the mashed part of the ribs.
3. The combination of a pair of dies adapted to act on opposite sides of the shank of a T-slug, said dies being provided with means for distorting a portion of the sides of the slug while leaving a portion thereof intact.
4. The combination of a pair of dies adapted to act on opposite sides of the shank of a T-slug, said dies being provided with means for mashing the upper portion of ribs on the sides of the slug while leaving the lower portion of such ribs intact.
5. The combination of a pair of dies adapted to act against the opposite sides of a T-headed slug, said dies being provided with means for mashing the upper portion of ribs on the sides of the slug and with means for shearing off the shank of the slug.
6. The combination of a pair of coacting dies provided with knife edges adapted to shear off the body portion of a slug, and projections carried by said dies adapted to engage and mash portions of ribs on the sides of said slug.
7. The combination of a pair of coacting dies and a pair of blades carried by the dies and having a movement independently thereof, said blades being adapted when the dies are separated to support a T-headed slug, and when the dies are brought together to mash portions thereof.
8. The combination of a pair of coacting dies each provided with a blade movably mounted therein, springs tending to cause said blades to approach each other, and means for causing the dies to approach or recede.
- 55 9. The combination of a pair of dies each provided with a knife edge and each provided with a movable blade, there being space for said blades to recede within the dies, whereby they may act to support a slug when the dies are separated and to press in the sides of the slug when the dies are brought toward each other.
- 60 10. The combination of a pair of dies each provided with a knife edge and each provided with a movable blade, there being space for said blades to recede into the dies, and springs adapted to force the blades toward each other to make a support for the slugs when the dies are separated.
11. The combination of a pair of coacting dies adapted to press in portions of ribs on the sides of a slug, and a pressing device adapted to press down on the face of the slug.
- 70 12. The combination of a pair of coacting dies adapted to press in portions on the sides of a slug and knives to shear off the lower part of the slug, and a pressing device adapted to press downwardly on the face of the slug to hold it firmly on said dies.
- 75 13. The combination of a pair of coacting dies each provided with a blade movable in the die, said blades being adapted to support a T-headed slug when the dies are separated and press against the sides of the slug shank when the dies are brought together, and means for forcing on the face of the slug to force the T-head thereof firmly against the blades.
- 80 90 14. The combination of a pair of coacting dies, one of which is movable, said dies having means to press in the sides of a slug between them, a roller, and means for forcing it against the face of such slug.
- 85 95 15. The combination of a pair of coacting dies, one of which is movable, said dies having means to press in the sides of a slug between them, a slightly yielding roller, and means for forcing it against the face of such slug to firmly seat the slug without injuring its characters.
- 100 16. The combination of a pair of dies adapted to act on opposite sides of the shank of a T-slug, said dies being provided with means for mashing the upper portion of ribs on the sides of the slug while leaving the lower portion of such ribs intact, and means for pressing the slug downwardly so that it is seated on its T-head.
- 105 110 17. The combination of a pair of dies adapted to act against the opposite sides of a T-headed slug, said dies being provided with means for mashing the upper portion of ribs on the sides of the slug and with means for shearing off the shank of the slug, and a roller adapted to press against the face of the slug.
- 115 18. The combination of a stationary die, a coacting movable die, each formed to indent the sides of a line slug, means for forcing the movable die toward or from the stationary die, and means for pressing down on the slug.
- 120 19. The combination of a stationary die, a coacting movable die, each formed to indent the sides of a line slug, a wedge for forcing the movable die toward or from the stationary die, and a lever for moving said wedge.
- 125 130

20. The combination of a stationary die, a coacting movable die, a wedge for forcing the movable die toward or from the stationary die, a lever for moving said wedge, a pressing device adapted to engage the face of the slug held between the dies, and a lever for operating the pressing device.
21. The combination of a pair of dies, formed to indent the sides of a line slug, a longitudinally movable wedge connected with one of the dies, a rack on said wedge, and a lever geared with said rack, whereby the operation of the lever may force the movable die toward the other die.
22. The combination of a pair of dies, a longitudinally movable wedge connected with one of the dies, a rack on said wedge, a lever geared with said rack, whereby the operation of the lever may force the movable die toward the other die, said dies being provided with coacting knife edges to shear off a portion of the slug between them.
23. The combination of a stationary die, a movable block, a die mounted thereon coacting with the die first mentioned, said dies being provided with knife edges and with pressing blades movably mounted within the dies, a movable wedge slidably connected with the block, a pressing device adapted to act on the face of the slug, and a lever for operating the pressing device and the movable wedge.
24. An apparatus for forming line slugs consisting of mechanism for holding a slug with ribs on its opposite sides, mechanism for shearing the base portion of the slug, and mechanism for pressing in a portion of the sides of the ribs.
25. In an apparatus of the class described, the combination of mechanism formed to engage and hold a slug with a shank, a T-head, and ribs on opposite sides of the shank leading to the T-head, and mechanism for shearing off the base portion of the slug.
26. In an apparatus of the class described, the combination of mechanism for holding a slug with a shank and ribs on opposite sides of the shank, and mechanism for shearing off the base portion of the shank and ribs and pressing inwardly the upper portion of the ribs, said shearing and pressing operation occurring simultaneously.
27. The combination, with a pair of coacting dies adapted to press in portions on the opposite sides of a T-headed slug, of a device for pressing the T-head onto the dies, the dies being inclined where they engage the under surface of the T-head to present a sharp edge to the head.
28. The combination, with a pair of coacting dies adapted to support a T-headed slug, means for causing said dies to approach each other to press in sides of the T-headed slug, the upper surface of said dies being inclined downwardly from their op-
- posed faces to present an edge against which the head rests, and means for pressing such head against such edge.
29. In a device of the character described, the combination of a pair of centering dies adapted to engage opposite sides of the head of a T-slug, and a pair of pressing dies adapted to approach each other to press in the sides of the slug.
30. The combination of a pair of centering dies adapted to engage opposite sides of the head of a T-slug having ribs on the opposite sides of its shank, a pair of pressing dies below the centering dies and adapted to extend inwardly beyond the centering dies and engage the under face of the head and support the slug, means for forcing the slug downwardly onto the pressing dies, and means for moving the pressing dies toward each other.
31. The combination, with means for holding a slug having a T-head and up and down ribs on its sides, of means for engaging opposite sides of the T-head to center the slug, and means for pressing in the ribs from opposite sides immediately beneath the head while leaving a portion of the ribs intact farther from the head.
32. The combination of a pair of centering dies having parallel opposed faces, a pair of pressing dies having parallel opposed faces and located below the centering dies and projecting inwardly beyond them, a pair of knives below the pressing dies, means for pressing downwardly a slug whose head is between the centering dies and whose shank is between the pressing dies and knives, and means for reducing the distance between the two elements of each pair mentioned.
33. The combination of a pair of centering dies having parallel opposed faces, a pair of pressing dies adjacent to the centering dies and projecting inwardly beyond them, a pair of knives adjacent to the centering dies, there being space between the two elements of the said pairs for the insertion of a slug, and means for reducing the distance between the two elements of each pair.
34. The combination of a pair of centering dies having parallel opposed faces, a pair of pressing dies adjacent to the centering dies and projecting inwardly beyond them, a pair of knives adjacent to the pressing dies, there being space between the two elements of the said pairs for the insertion of a slug, means for reducing the distance between the two elements of each pair, and means extending lengthwise of the slug and adapted to press against the face of it to seat it against the pressing dies.
35. The combination of a pair of dies adapted to act against the opposite sides of a T-headed slug, said dies being provided

with means for distorting a portion of the slug while leaving a portion thereof intact, and with means for shearing off the shank of the slug.

36. The combination of a pair of coacting dies provided with knife edges adapted to shear off the body portion of a slug, and projections carried by said dies adapted to engage and distort the sides of said slug.

37. The combination of a pair of coacting dies and a pair of blades carried by the dies and having a movement independently thereof, said blades being adapted when the dies are separated to support a T-headed slug, and when the dies are brought together to distort portions thereof.

38. The combination of a pair of dies adapted to act on opposite sides of the shank of a T-slug, said dies being provided with means for distorting a portion of the sides of the slug while leaving a portion thereof intact, and means for pressing the slug downwardly so that it is seated on its T-head.

39. The combination of a pair of dies

adapted to act against the opposite sides of a T-headed slug, said dies being provided with means for distorting a portion of the sides of the slug while leaving a portion thereof intact and with means for shearing off the shank of the slug, and a roller adapted to press against the face of the slug.

40. An apparatus for forming line slugs consisting of mechanism for holding a slug, mechanism for shearing the base portion of the slug, and mechanism for distorting a portion of the sides of the slug.

41. The combination, with means for holding a slug having a T-head and a body, of means for engaging opposite sides of the T-head to center the slug, and means for pressing against the body from opposite sides below the head while leaving a portion of such body intact.

In testimony whereof, I hereunto affix my signature in the presence of two witnesses.

HARRY C. GAMMETER.
